MUFFLER

Virgil Oldberg and William C. Morgan, Jr., Detroit, Mich., assignors to Oldberg Manufacturing Company, Detroit, Mich., a corporation of Michigan

Application August 31, 1932, Serial No. 631,188

1 Claim. (Cl. 137—160)

This invention relates to mufflers.

The principal objects of the invention are novel muffler combinations employing parts which provide resonance chambers in the mufflers, the mufflers being so constructed as to provide an extremely low back pressure, consistent with effective silencing.

Still further objects will be observed upon reference to the following detailed description of an embodiment of the invention, this embodiment being shown in the appended drawing.

The figure shows in sectional elevation one form of muffler.

The muffler of the figure includes an outer shell 30, an intermediate shell 31 and an inner shell 32. In the right or inlet end of the shell 30 there is disposed an inlet head 34 having a portion drawn out of the muffler to provide an inlet 36. In the outlet end of the muffler there 20 is disposed an outlet head 35 having an outlet portion 37.

The intermediate shell 31, connected to the outlet head 35, does not extend all the way to the inlet head 34 but is spaced therefrom a slight 25 distance and is connected at the inlet end to the outer shell 30 by a plate 38 as indicated. The inner shell 32, also connected to the outlet head 35, has its right end spaced from the inlet head 34 a considerable distance, this end of the 30 inner shell being closed by a plug 39.

The intermediate shell is provided with a plurality of relatively large holes 40 near the inlet end of the muffler, and is also provided with a second series of relatively large holes 41 closely 35 adjacent the outlet head 35. A baffle plate 42 disposed intermediate the holes 40 and 41 connects the intermediate shell to the outer shell and forms resonance chambers R^3 in the space between these shells, it being observed that as 40 many of these baffles may be provided as desired, the embodiment shown having but one of these baffles.

The inner shell is connected to the intermediate shell 31 by a plurality of baffles 45 which 45 form sound wave attenuating chambers R^4 in the space between the inner and intermediate shells, there being as many of these baffles as desired to form as many chambers R^4 as desired. That portion of the inner shell between its 50 plugged end and the righthand one of the baffles 45 is covered with a large number of small holes 46. The remainder of the inner shell, that is to say, that portion thereof between the righthand baffle 45 and the outlet 37 is covered with 55 a large number of closely spaced and outwardly

extruded minute perforations 47, preferably slightly smaller than the perforations 46.

The operation and functions of the construction are as follows: Exhaust gases enter the muffler through inlet 36 and pass into the expansion chamber C provided in the intermediate shell 31 between the baffle 45 and the inlet end of the muffler. The gases expand freely in this expansion chamber and a portion of them pass into the outer resonance chamber R^3 through the 60 holes 40. Another portion of the gases enters the inner shell through the small holes 46, from where they pass unobstructed through the outlet 37, this much of the muffler being in the nature of a through muffler. A portion of the 65 gases that enter the inner shell escapes through perforations 47 into the inner chambers R^4 between baffles 45. A still further portion of the gases escape from the lefthand inner chamber R^4 to the righthand outer resonance chamber R^3 70 through the holes 41 of the intermediate shell.

The construction of the figure, while not exactly a through muffler, there being at least one interruption to the unobstructed flow of exhaust gases from inlet 36 to outlet 37, nevertheless is of the low back pressure type, and is an effective silent muffler. The expansion chamber C in the inlet end of the intermediate shell 31, prevents an undue rise in the back pressure, 75 as will readily be seen.

Now having described one embodiment of the invention, reference will be had to the following claim which determines the scope of the invention, it being observed at this time that the invention is not to be limited to the specific details and proportions heretofore shown and described.

What we claim is:

In a silencer having an inlet head at one end 95 and an outlet head at the other, the combination of three relatively telescoped shells, the innermost of which has a closure near the inlet head, the space between the inlet head and the closure forming an unrestricted expansion chamber into which the inlet opens, the innermost shell being connected to the next adjacent or intermediate shell by a plurality of transverse annular diaphragms forming longitudinally spaced chambers around the inner shell, the inner shell having near its inlet end a plurality of holes through which gases pass from the expansion chamber to the inside of the inner shell, the inner shell also having a substantial area covered with a plurality of perforations opening to

the chambers, the inner shell also opening to the outlet of the silencer, the intermediate shell having a plurality of holes at the expansion chamber for communicating the latter chamber with the space between the intermediate shell and the outer shell, there being annular chamber-forming means between the outer shell and the inter-

mediate shell, the intermediate shell also having holes near the outlet end intercommunicating the spaces on opposite sides of the intermediate shell.
